UNITED STATES PATENT OFFICE.

IRVING BORUCHOW, OF BROOKLYN, NEW YORK.

DESIGN FOR A MANICURING INSTRUMENT.

Application filed February 2, 1925. Serial No. 12,236. Term of patent 3½ years.

To all whom it may concern:

Be it known that I, IRVING BORUCHOW, a citizen of Poland, residing at 93 South 10th Street, in the city of Brooklyn, county of Kings and State of New York, and doing business in Brooklyn, N. Y., have invented a new, original, and ornamental Design for Manicuring Instrument, of which the following is a specification, reference being had to the accompanying drawings, forming part thereof.

I claim:

The ornamental design for a manicuring instrument as shown.
